UNITED STATES PATENT OFFICE.

FRANK X. STURM, OF ALEXANDRIA, INDIANA, ASSIGNOR TO THE GLOVE CORPORATION, OF ALEXANDRIA, INDIANA, A CORPORATION OF INDIANA.

GLOVE.

Application filed November 12, 1926. Serial No. 147,883.

My invention relates to improvements in gloves and particularly to a blank for forming the backs of the fingers of a glove. My invention is especially directed towards a 5 blank for forming the backs of the fingers of workmen's gloves and particularly of that type of glove which is formed partially of one material, preferably leather, and partially of another material, such for instance 10 as fabric.

It is one of the objects of my invention to provide a blank for the formation of the backs of the fingers of a glove which will permit of the cutting of the blank, either 15 in a single or multiplicity of pieces with a minimum of waste material.

For the purpose of disclosing my invention I have illustrated certain embodiments thereof in the accompanying drawings, in 20 which,

Fig. 1 is a rear elevation of the fingers of a glove having the backs thereof formed from a blank embodying my invention;

Fig. 2 is a view of the blank employed in 25 forming the backs of the fingers shown in Fig. 1;

Fig. 3 is a view of another glove, the backs of the fingers of which are formed from a blank embodying my invention;

Fig. 4 is a view of a modified form of the blank shown in Fig. 2 and which when folded and stitched will form the fingers as shown in Fig. 3.

Fig. 5 is a detail view of still another 35 modification of the blank, only the center opening being shown;

Fig. 6 is a rear elevation of a glove embodying a modification of my invention, and

Fig. 7 is a view of the blank forming the 40 backs of the fingers illustrated in Fig. 6.

In the embodiment illustrated in Fig. 2 the blank preferably comprises a single piece of material and is cut to provide a substantially star shaped figure having the points 45 1, 2, 3 and 4. At its center this blank is provided with a central opening 5 of such shape that in the base of each of the points 1, 2 and 3 there is formed a V shaped notch such 50 as at 6, 7 and 8. The material of the point 4 at its base is slit for a short distance from the base outwardly on a line extending radially outwardly through the center of the point 4 as at 9 and is again slit at right angles to the slit 9 and on a line 10 which forms

a continuation of one edge 11 of the point 1. The slitting of the material at 9 and 10 disconnects the two points 1 and 4 so that the material may be folded on the radial lines 12.

When the blank is assembled in a glove the material is folded so that each of the points 1, 2, 3, and 4 lies parallel with the other, the material doubling or folding along the lines 12, and the outer edges of the 60 points are stitched or sewed to the front finger portions of the palm or front finger blank. The walls of the opening 5 form the lower or bottom edge of the fingers and this edge is stitched to the fabric forming 65 the back of the glove.

In Fig. 4 the center opening 13, which corresponds to the opening 5, is somewhat circular in shape and a single slit 14 is made along the base of the point 4 instead of the 70 rectangular slit as in Fig. 2. This slit 14, however, as in the structure illustrated in Fig. 2, forms a continuation of an edge 15 of the finger piece 1. In folding and assembling the blank is handled in the same manner as the blank illustrated in Fig. 2.

In Fig. 5 the center opening 16 is triangular in shape, the slit 17 in the base of the point 4 however being the same as that shown in the structure illustrated in Fig. 4 85 and forming a continuation of the edge 18 of the point 1.

In Fig. 7 the center opening 19 is substantially rectangular in shape, the corner occurring at the line, 12, of fold. In this 90 figure the slit 20 is made in the base of the point 1 substantially at right angles to the edge thereof and the slitted portion forms a continuation of the edge 21 of the point 4.

It will be noted, however, that in all of 95 the structures illustrated there is provided in the blank a center opening and that the material of the base of one of the points of the star is slit substantially at right angles to the edge of the point and that this slit 100 thus forms a continuation of the edge of one of the other points.

I claim as my invention:

1. A blank for the backs of the fingers of a glove comprising a substantially star 105 shaped blank having an aperture at its center and its points constituting the backs of the fingers, two of the points of the blank being separated on a line extending transversely into the base of one of the points 110

of the star and forming a continuation of one edge of another point of the star.

2. A blank for the backs of the fingers of a glove comprising a substantially star shaped figure having a central opening formed therein, two of the points of the star being separated on a line extending into the base of one of the points substantially at right angles to the edge of the point and

forming a continuation of the edge of one of the other points, and on a second line extending at right angles to the first mentioned line and to the edge of the center opening.

In witness whereof I, FRANK X. STURM, have hereunto set my hand at Columbus, 15 Ohio, this 6th day of November, A. D. one thousand nine hundred and twenty-six.

FRANK X. STURM.
